UNITED STATES PATENT OFFICE.

HALBERT E. PARKHURST, OF FITCHBURG, MASSACHUSETTS, ASSIGNOR TO
THE BEOLI COMPANY, OF SAME PLACE.

DESIGN FOR WOVEN FABRIC.

SPECIFICATION forming part of Design No. 24,746, dated October 8, 1895.

Application filed August 18, 1895. Serial No. 559,559. Term of patent 3½ years.

To all whom it may concern:

Be it known that I, HALBERT E. PARKHURST, of Fitchburg, in the county of Worcester and State of Massachusetts, have invented and produced a new and original Design for Woven Fabrics, of which the following is a description.

Reference is to be had to the accompanying drawing, which shows a plan view of a woven fabric embodying my design.

The leading feature of my design consists in a number of elongated tuft-like figures raised from the surface of the fabric in an irregular manner and of varying lengths and thicknesses.

Referring to the drawing, A designates the

base or body of the fabric, of woolly appearance.

A' shows long tuft-like figures tapering irregularly from one end to the other, and A² indicates shorter tuft-like figures also having a taper from one end to the other.

The several tuft-like figures are shown as having a substantially-diagonal trend with relation to the body-fabric.

I claim—

The design for a fabric substantially as herein shown and described.

HALBERT E. PARKHURST.
